GENTLEMEN'S NECK WEAR.

No. 19,597.

Patented Jan. 21, 1890.

UNITED STATES PATENT OFFICE.

LESTER S. HILLS, OF CHICAGO, ILLINOIS.

DESIGN FOR GENTLEMEN'S NECK-WEAR.

SPECIFICATION forming part of Design No. 19,597, dated January 21, 1890.

Application filed October 10, 1889. Serial No. 326,588. Term of patent 14 years.

To all whom it may concern:

Be it known that I, LESTER S. HILLS, a citizen of the United States, residing at Chicago, in the county of Cook and State of Illinois, 5 have invented and produced a new and original Design for Gentlemen's Neck-Wear, which is fully set forth in the following specification, reference being had to the accompanying photograph, forming a part hereof.

10 The accompanying drawing shows my new and original design for gentlemen's neck-wear in front view.

The leading feature of my design consists in the ornamentation of the knot portion of 15 a scarf or necktie, comprising a roughened,

irregular, or ruffled or shirred surface—such, for example, as is shown in the accompanying photograph, in which A denotes the necktie, and B the ruffled or shirred knot thereof.

What I claim is—

20 The design for gentlemen's neck-wear wherein the surface of the knot B thereof is provided with ornamentation consisting of irregular surfaces, substantially as shown and described.

LESTER S. HILLS.
